(57) **CLAIM**

The ornamental design for a fire starter, as shown and described.

DESCRIPTION

FIG. 1 is a top perspective view of a fire starter showing a first embodiment of our new design;

FIG. 2 is a bottom perspective view thereof;

FIG. 3 is a front view thereof, the rear view being a mirror image of the front view;

FIG. 4 is a left side view thereof;

FIG. 5 is a right side view thereof;

FIG. 6 is a top view thereof; and

FIG. 7 is a bottom view thereof.

FIG. 8 is a top perspective view of a fire starter showing a second embodiment of our new design;

FIG. 9 is a bottom perspective view thereof;

FIG. 10 is a front view thereof, the rear view being a mirror image of the front view;

FIG. 11 is a left side view thereof;

FIG. 12 is a right side view thereof;

FIG. 13 is a top view thereof; and,

FIG. 14 is a bottom view thereof.

The broken lines shown in the drawings illustrate portions of the fire starter that form no part of the claimed design.
